UNITED STATES PATENT OFFICE

1,937,156

SYSTEM OF BEATER ENGINES

William V. Knoll, Dayton, Ohio, assignor to The
Midwest-Fulton Machine Company, a corpora-
tion of Ohio

Application June 28, 1928. Serial No. 288,857

26 Claims. (Cl. 92—20)

My invention relates to pulp making and fiber liberation, and more particularly to a process and apparatus for the progressive treatment of pulp for paper making and other purposes in a con-

tinuous flow stream in which the pulp is automatically advanced through the successive stages of preparation.

The present apparatus is employed in lieu of a series of the customary Hollander type of beaters

wherein the pulp follows a circuitous path of repetitious beating in each succeeding tub, the conditioned stock being transferred from one tub to another. In the present system and apparatus

there is employed a plurality of beater rolls each housed in a concave setting having therein the customary bed plate co-acting with the roll, which units are interconnected in series by intermediate conveyors to receive the material from one beater roll and discharge it to the next beater

roll for successive beating action throughout the system. The pulp is thus worked without cessation or interruption from the digestor or grinder until it is ready for use upon the paper making machine. The conditioned pulp may be dis-

charged into a common offtake conveyor at any stage of the successive operations, thus making the system extremely flexible and enabling the simultaneous different treatment of distinctly different kinds of fiber. Soda pulp and sulphite

pulp, sulphite pulp and ground wood, or rags and sulphite pulp, or other desired combinations may be initially beaten separately and subsequently mixed together in the desired proportion at any predetermined point in the process to receive fur-

ther combined treatment. Furthermore the steps of claying, sizing and coloring may be performed automatically and continuously with the beating or fiber liberating and shortening operations.

The object of the invention is to simplify the apparatus as well as the means and mode of operation of pulp and fiber treatment and preparation, whereby the successive steps of treatment and preparation may be continuously performed

without cessation or interruption and to provide an apparatus which will be compact, and which will require minimum power for operation, uniform in its action, substantially automatic in operation, and unlikely to get out of repair.

It has been conservatively estimated that an installation of eight rolls in the present system will occupy the floor space of two Hollander type beaters and will deliver approximately twenty-five tons of pulp per hour, which is the equivalent output of twenty-five Hollander type beaters with

a power requirement of 225 H. P. as compared with a power requirement of 2000 H. P. of such twenty-five Hollander beaters delivering a like amount.

A further object of the invention is to provide a system and method of great flexibility and capable of handling a wide variety of materials including sulphite stock, soda stock, kraft stock, ground wood, bagasse, rope, jute, rag and mixed paper stock, and furthermore any two or more of these materials may be simultaneously treated and subsequently intermixed for further working in combination.

A further object of the invention is to provide for the agitating and hydrating of the stock while in the intermediate conveyors between succeeding beater rolls of the system.

With the above primary and other incidental objects in view, as will more fully appear in the specification the invention consists of the features of construction, the parts and combinations thereof, and the mode of operation, or their equivalents, as hereinafter described and set forth in the claims.

Referring to the accompanying drawings, wherein is shown the preferred, but obviously not necessarily the only form of embodiment of the invention, Fig. 1 is a plan view of a duplex system of arrangement of beater rolls involving the present invention. Fig. 2 is a somewhat diagrammatic view showing successive units of the system in cross section and indicating the transferance of the material from one such unit to the other. Fig. 3 is a side elevation of a modification of the system wherein the succeeding beater rolls are located on different levels and the stock transferred from one unit to another by gravity. Fig. 4 is a top plan view and Fig. 5 a front elevation of the gravity operated system illustrated in Fig. 3. Fig. 6 is a detail sectional view of a modified form of beater roll of the rod mill type which is used at one or more points throughout the system. Fig. 7 is a longitudinal sectional view of a portion of the beater roll illustrated in Fig. 6.

In the present construction each of the beater units comprises a beater roll or drum 1 which is ordinarily provided with the usual protruding fly bars or may be provided with rollers or beater bars about its periphery by which the pulp fibers are beaten, rubbed or cut as the character of the material and its purpose or condition of use may require. These beater rolls 1 are located in concave housings 2 which substantially conform to a considerable portion of the periphery of the beater rolls 1. Such concave housings or set-

tings 2 are reversely curved at opposite sides of the beater roll or drum 1 to provide a gradually contracting receiving throat 3 at the intake side of the roll and to provide what is in effect a backfall 4 at the opposite or discharge side of the roll. Located at the bottom of each of such concave housings or settings 2 is the usual bed plate 5 which may be of any desired extent and construction in accordance with the type of roll and character of the work to be performed at the particular stage of operation. The pulp to be operated upon is discharged into the throat 3 of the concave housing or setting, preferably though not necessarily, from a screw conveyor 6 by which it is conducted from the preceding beater unit or other pulp treating mechanism. Such pulp continuously discharged into the throat 3 is subjected to a squeezing or compressing action of the roll or drum as the latter rotates carrying the pulp downwardly between the roll and the concave wall of the housing. The squeezing and rubbing action preceding the passage of the pulp between the bed plate 5 and the roll 1 greatly facilitates the fiber separation and better conditions the pulp for treatment over the bed plate. The treated pulp is carried upwardly by the rotation of the drum 1 and is discharged over the rearward outwardly flaring wall of the housing or setting 2 in quite the same manner as pulp is ordinarily discharged over the usual backfall. This discharged pulp is received in a second conveyor by which it is conducted to the next succeeding beater unit. During its progress through the conveyors between succeeding beater units the pulp is subjected to a constant hydrating and stirring action or agitation which facilitates the liberation of the fibers and reduces it to a uniform consistency preparatory to reworking.

Such beater units with their interposed conveyors connecting them in series may be successively continued to any extent.

In Fig. 1 of the drawings, two independent series of such beater units are shown. For convenience of arrangement and saving of space the beater units are arranged in staggered relation in which the alternating beater units are disposed in parallel rows. The succeeding units are interconnected by the conveyors 7-7 which receive the beaten pulp at the output side 4 of one beater unit and discharges into the intake side or throat 3 of the succeeding unit. Pulp entering the first unit of the series from the digestor or storage tank is conducted successively through any desired number of the beater units, and when the pulp is reduced to the desired consistency it is discharged into a common offtake conveyor 9 through an extension 8 of one of the intermediate conveyors 7. The conveyor 9 which may receive pulp at any intermediate stage of operation carries the pulp through successive stages of coloring, claying, sizing, etc. The various tanks or receptacles for supplying the coloring, filling and sizing materials communicates directly with the common conveyor 9 as shown at 10 and 11, or such conveyor 9 may discharge into a system of segregating conveyors illustrated at 12, 13 and 14, with the branch conveyors of which the various color, sizing and filling tanks or vessels communicate as illustrated at 15, 16 and 17.

To provide for the treatment of pulp of different character which may be later combined, one kind of pulp may be introduced into the first beater unit of the series and after having traversed a predetermined number of such units it

may be discharged into the conduit extension 8 into the common offtake conduit 9. At the same time pulp of different character may be fed through a succeeding plurality of the same series of beater units, and after having traversed the desired number of units such pulp of different character may be discharged into the same offtake conduit wherein the two kinds of beaten pulp are intermixed with each other. In Fig. 1 of the drawings there are shown two entirely distinct systems each comprising a plurality of beater units and two offtake conveyor conduits 9. The conduit extension 8 leading from the beater units of each of the separate systems are adapted to discharge into either of the offtake conveyor conduits 9 at will. These conveyors are provided with gates or valves, which by their adjustment may connect the different beater units of either of the systems with either of the offtake conveyor conduits 9. It is also understood that the conveyor conduits 7 are provided with valves or gates, whereby instead of discharging normally into the intake side of a beater unit such conveyors may be caused to discharge through the conduit extension 8 into either of the offtake conveyor conduits 9. This arrangement allows great flexibility in the operation of the system and the treatment of the pulp, permitting the pulp to be discharged into the offtake conveyor 9 at any desired stage of operation. Thus a quantity of pulp may be caused to continue through the entire series of beater units of the system or it may be released into the offtake conveyor conduit 9 after having passed through any desired portion of such beater units, in which case if so desired, pulp of different characters may be simultaneously treated in the succeeding beater unit for discharge into the same offtake conveyor conduit 9 or into a different offtake conveyor of which two have been shown. A gate or valve 18 in the distributing system separates the material from the respective offtake conveyors 9 so that such material is not necessarily intermixed.

Fig. 2 shows transverse sectional views of several beater units of the series illustrating how the discharge conveyor conduit of one unit becomes the intake or supply conveyor for the succeeding unit. While screw conveyors are preferably employed for transferring the material through the intermediate conduits and for simultaneously agitating and hydrating the beaten pulp, such pulp may be conveyed from one unit to another by gravity.

Such gravity operated system is shown in Figs. 3, 4 and 5, wherein the beater rolls 1 and their concave housings 2 are located at different levels as more clearly shown in Fig. 3. The pulp is initially supplied to the beater unit on the highest level and is discharged from the output side of each beater unit to the intake of the succeeding beater unit on the next lower level. However as shown in Fig. 4 the beater units are offset laterally relative to each other on the different level so that the beaten pulp is made to travel a greater or less distance through the intermediate conveyor in quite the same manner as is illustrated in Fig. 1. During the travel of the beaten pulp through the conveyor system from one beater unit to another, whether it be by means of screw conveyors as in Fig. 1 or by gravity as in Figs. 3 to 5, the beaten pulp is subjected to more or less agitation which causes the water to penetrate more thoroughly into the beaten fiber, causing the fibers to be

separated and intermixed to a uniform consistency. While Fig. 3 shows the successive beater units located at different levels, Fig. 5 shows the incline of the conveyors which carry the stock successively through the different beater units, each located on a lower level.

While, as before mentioned, the beater rolls 1 may be provided with rigid fly bars as is the common practice it is preferable that one or more rolls of the series be provided with loosely mounted peripheral rollers projecting somewhat beyond the periphery of the drum and capable of a limited lateral movement. As shown in Fig. 6 the periphery of the drum or roll 1 is provided with a plurality of closely spaced peripheral grooves or pockets 21 within each of which is mounted a rather heavy roller 22. Such rollers 22 have terminal trunnions 23 loosely engaged in enlarged openings in the shrouds of the rolls. The peripheral rollers 22 are thus permitted a limited degree of freedom, and as the drum rotates such peripheral rollers fall onto the pulp being treated with a beating action, giving to it a bruising or impacting effect somewhat analogous to rod mill treatment.

While in the drawings the beater units have been shown successively disposed in offset or staggered relation to afford a more extended intermediate run of conduits or conveyors 7 to insure more thorough hydration and agitation of the pulp preparatory to each beating operation, it is to be understood that these beater units may be disposed closely in the single course, in which the pulp discharged over the output 9 or backfall 4 of one beater unit enters immediately into the throat of the succeeding unit. Of course in such arrangement means is provided for diverting the flowing pulp at any desired stage of operation into an offtake conveyor or conduit 9 so that the treatment may be arrested when the desired condition is reached and the remaining units of the series employed for treating an additional body of pulp of the same or of different character.

From the above description it will thus be seen that there is provided a device of the character described, possessing the particular features of advantage, before enumerated as desirable, but which obviously is susceptible of modification in its form, proportions, and arrangement of parts, without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise the preferred form of several modes of putting the invention into effect, and the invention is therefore claimed in any of its forms or modifications within the legitimate and valid scope of the appended claims.

I claim:

1. In an apparatus for the progressive treatment of pulp, a plurality of beater units arranged in groups each including a revoluble beater roll and a receiver in which the roll is mounted, said receivers being formed with a pulp receiving portion at one side of the roll and a pulp discharge portion at the opposite side of the roll and means successively connecting the discharge outlets of the units of each group with the intake portions of the succeeding units of the same group whereby the entire output of each beater roll is sup-

plied to the succeeding beater roll of the group, and a common outlet for the beater units of the several groups, through which the intermixed output of the several groups of beater units is discharged.

2. In an apparatus for the progressive treatment of pulp, a plurality of beater units each including a revoluble beater roll and a receiver in which the roll is mounted, a pulp receiving extension at one side of each receiver, and a pulp discharge extension at the opposite side of the receiver, a plurality of intermediate conveyors interconnecting the discharge extension of one receiver with the intake extension of the succeeding receiver and means for interrupting the continuity of discharge of the beater units from one to another, and a common conveyor into which different units of the plurality may be made to simultaneously discharge.

3. In an apparatus for the progressive treatment of pulp, a series of beater rolls, settings therefor, the output of one beater roll being connected with the input of another beater roll, an offtake conveyor common to a plurality of the beater rolls, and means for diverting the output of pulp from a succeeding beater roll into said offtake conveyor at different points in the series of beater rolls.

4. In an apparatus of the character described, a plurality of beater units each comprising a revoluble beater roll and a setting therefor, the output of one beater roll being connected with the intake of another beater roll, said beater units of the series being separable into groups wherein stock of different character may be fed through the beater units of the different groups, and a receiving conduit common to the beater units of both groups into which the finished stock from both groups of units may be discharged for intermixture and further unison treatment.

5. In an apparatus for the treatment of pulp, a plurality of beater units each including a revoluble beater roll and a concave setting therefor having a pulp receiving portion at one side of the roll, and a pulp discharge portion at the opposite side of the roll, succeeding units being arranged in staggered relation in two lineal series and intermediate conduits connecting the output portions of units of one series with the input portions of units of the other series, the pulp being conducted in a continuous progression through the succeeding units of the plurality.

6. In an apparatus of the character described, a succession of beater units each including a revoluble beater roll, a setting therefor, a pulp supply conveyor extending in parallel relation with the beater roll at one side thereof, and a pulp discharge conveyor extending in parallel relation with the beater roll at the opposite side of the roll, said conveyors connecting the output side of one unit with the intake side of the succeeding unit of the succession.

7. In an apparatus of the character described, a succession of beater units each including a revoluble beater roll, a concave setting therefor, a pulp receiving portion at one side of the roll, and a pulp discharge portion at the opposite side of the roll, conveyors connecting the discharge portion of one unit with the receiving portion of another unit, an offtake conveyor common to a plurality of units of the succession and pulp outlet connections intermediate succeeding units of the series through which the pulp may be discharged into said common offtake conveyor at intermediate stages of operation.

8. In an apparatus of the character described, a plurality of beater units each including a revolvable beater roll, a concave setting therefor, a pulp intake portion at one side of the roll and a pulp discharge portion at the opposite side of the roll, said plurality of beater units being divided into separate series, conveyor conduits connecting the discharge portion of each unit with the intake portion of another unit of the same series, an offtake conduit common to the units of both series and outlet connections for discharging pulp into said common conduit at intermediate stages of operation of the units of the respective series. 80
- 15 9. In an apparatus of the character described, a plurality of beater units each including a revolvable beater roll, a concave setting therefor, a pulp intake portion at one side of the roll and a pulp discharge portion at the opposite side of the roll, said plurality of beater units being divided into separate series, conveyor conduits connecting the discharge portion of each unit with the intake portion of another unit of the same series, separate offtake conveyor conduits and outlet connections connecting the discharge portions of units of the different series with both said offtake conduits, and cutoffs whereby such discharge may be directed to one or the other of the offtake conduits at will. 90
- 20 10. In a beater unit for pulp, a rotary drum, a concave housing substantially conforming to the lower segmental shape of the drum, the opposite ends of such concave housing being outwardly flared at opposite sides of the drum to afford parallel supply and discharge channels communicating with such flared portion, a gradually contracting receiving throat at the intake side of the drum into which the supply conduit laterally discharges and a backfall over which the pulp is discharged at the output side of the drum over which the material is discharged laterally into the discharge conduit, said supply and discharge conduits conducting the material to and away from the roll in directions substantially parallel therewith. 100
- 25 11. A beater unit for pulp, comprising a revolvable beater roll, a concave housing conforming to the lower periphery of the roll within which the roll is positioned, said concave housing being extended upwardly in flaring relation with the periphery of the roll at the intake side thereof to form a gradually contracting throat into which the material operated upon is received and a transverse supply conduit discharging laterally into said throat. 110
- 30 12. A beater unit for pulp including a revolvable beater roll, a concave receptacle within which the roll is concentrically mounted, said receptacle being extended upwardly in flaring relation with the periphery of the roll at both the front and back thereof and supply and discharge conduits conveying material to and from the roll in directions parallel therewith and communicating laterally with the flaring portions of the receptacle at opposite sides of the roll. 120
- 35 13. A beater unit for pulp including a revolvable beater roll, a concave receptacle within which the roll is concentrically mounted, said receptacle being extended upwardly in flaring relation with the periphery of the roll at both the front and back thereof, said flaring portions of the receptacle being of convex form and transverse supply and discharge channels communicating with such flaring portions of the receptacle. 130
- 40 14. The herein described method of pulp treatment consisting in the simultaneous progressive treatment of different batches of stock through succeeding intercommunicating beater units of different groups and simultaneously discharging the different batches of stock into a common conveyor conduit for intermixture and subjecting the mixed stock to further unison treatment while carrying on continuous operation. 140
- 45 15. A beater unit comprising a revolvable drum, a concave setting in which the drum is mounted, a pulp receiving portion at one side of the drum and a pulp discharge portion at the opposite side of the drum, said drum having a succession of longitudinally disposed pockets about its periphery, a plurality of rollers loosely journaled in said pockets for limited lateral movement under influence of gravity as the carrying drum rotates. 150
- 50 16. A beater unit comprising a revolvable drum, a concave setting in which the drum is mounted, a pulp receiving portion at one side of the drum and a pulp discharge portion at the opposite side of the drum, and a plurality of gravity operated members loosely mounted about the periphery of the drum and free for to and fro movement in radial directions impinging upon the pulp as the drum rotates. 160
- 55 17. A beater unit for pulp, including a revolvable beater roll, a concave housing within which the roll is mounted, and a conveyor located at the supply side of the roll through which the material is conducted to the roll in a direction substantially parallel with the axis thereof and from which such material overflows laterally from the conveyor extending into the housing beside the roll thereby tending to distribute material supplied to the roll throughout substantially the full length thereof. 170
- 60 18. A beater unit for pulp including a revolvable beater roll, a concave housing within which the roll is mounted, and a conveyor located at the discharge side of the roll extending below the level of the side wall of the housing and parallel with the roll through which the material is conducted away from the beater roll in a direction substantially parallel with the axis thereof and which receives the material laterally from the housing throughout substantially the full length of the roll. 180
- 65 19. A beater unit for pulp including a revolvable beater roll, a concave housing within which the roll is mounted, and supply and discharge channels extending in parallel relation with the roll at each side thereof for conducting the material to and from the roll in directions longitudinally thereof. 190
- 70 20. A beater unit for pulp, including a revolvable beater roll, a concave housing within which the roll is mounted, a supply channel extending in parallel relation with the roll at the receiving side of the housing and conducting the material longitudinally of the roll and discharging laterally into the housing beside the roll. 200
- 75 21. A beater unit for pulp, including a revolvable beater roll, a concave housing within which the roll is mounted, and a discharge channel extending in parallel relation with the roll at the discharge side of the housing and communicating laterally directly therewith for conducting the material away from the roll in a longitudinal direction relative thereto, said channel receiving the discharge from the housing throughout substantially the full length of the roll. 210
- 80 22. The herein described method of treating pulp, including separately treating different 220

5 batches of pulp while flowing in continuous separate streams progressively through successive stages, intermixing the separately treated streams of pulp and collectively subjecting the intermixed pulp from the separate batches to further treatment as a whole and collectively discharging the material as a single product.

10 23. The herein described method of treating pulp, including continuous operation of simultaneously beating separate batches of pulp each flowing in a separate stream through successive beaters, intermixing the separately beaten batches of pulp and collectively subjecting the intermixed pulp batches to further treatment

15 while flowing in a single stream.

20 24. The herein described method of treating pulp by separately treating different continuously flowing streams of pulp through successive beaters, uniting the different streams of pulp into a single continuously flowing stream and subjecting the pulp in such single stream to further treatment.
